LOOM SHUTTLE

Kenneth Massey and Richard Vernon Patchett,
Spondon, near Derby, England, assignors to
British Celanese Limited, a company of Great
Britain

Application September 29, 1950, Serial No. 187,494

3 Claims. (Cl. 139—208)

1

This invention relates to looms for weaving and particularly to loom shuttles.

In the Lancashire type of loom shuttle the shuttle tongue, on which the weft package or purn is mounted, is pivoted at its butt end near one end of the wooden body of the shuttle, in a slot forming a narrower extension of the cavity for accommodating the purn. The butt is acted upon by a tongue return spring which serves to hold the tongue either in the working position or in a raised position for the changing of the purn. The spring occupies the rear end of the slot, and a forwardly extending limb of the spring passes beneath the butt of the tongue to press against either the lower surface of the butt as the tongue lies horizontally in the shuttle, or against the heel or end surface of the butt when the tongue is raised. It is an object of the present invention to provide, in a shuttle, an improved arrangement of the shuttle tongue and shuttle tongue return spring, having certain advantages over the arrangement hitherto used.

According to the present invention a loom shuttle comprises a pivoted tongue for the reception of a weft package, and a spring adapted to exert pressure on the lower face of the butt of said tongue for maintaining said tongue in a working position and on the heel of said butt for maintaining said tongue in a raised position, every part of said spring whose resilience contributes to said pressure being disposed substantially wholly beneath said butt when said tongue is in the working position. This arrangement has the advantage that the tongue return spring does not take up any part of the length of the shuttle that is not already occupied by the butt of the tongue and so enables the pivot of the tongue to be disposed nearer the end of the shuttle and permits the length of the slot (measured in the direction of the length of the shuttle) to be reduced. This leaves a greater proportion of the length of the shuttle available for the purn cavity, and enables a larger purn to be accommodated.

The springs usually employed as the return springs for shuttle tongues are of the type that are bent through approximately 180°, so having two limbs one of which engages the butt of the shuttle tongue while the other engages the body of the shuttle. A similar type of spring can be employed for the purposes of the present invention but it is preferred that the limbs of the spring should extend rearward, rather than forward as hitherto. The bend of the spring can then be hooked round the pin already provided

2

in the shuttle for limiting the downward movement of the tongue and determining the working position of the tongue in the shuttle. This makes unnecessary the provision of a separate pin for the anchoring of the spring in the shuttle at a point to the rear of the shuttle tongue. An auxiliary spring, preferably constituting an extension of the spring disposed beneath the butt may be provided to exert an additional pressure on the heel of the butt when the tongue is in the working position and on the upper surface of the butt when the tongue is in the raised position. Such auxiliary spring or extension, however, since it extends in a direction transverse to the length of the shuttle, occupies only a negligible part of said length and does not substantially detract from the advantages above mentioned.

The slot in the wooden body of the shuttle, in which slot the tongue is pivoted, is liable to wear at the sides, thus allowing the tongue some lateral freedom and permitting the purn to vibrate against the sides of the shuttle. This defect gives rise to weft breakages, and is more serious when a large and heavy weft package is employed. It is a further feature of the present invention, in order to overcome this defect, to provide an insert of harder material than the wood of which the shuttle body is made, forming a lining for the sides of the slot and laterally confining the butt of the shuttle tongue. In this way, wear on the sides of the slot is reduced and the shuttle tongue is held firmly in the shuttle. This insert can be made of mild steel but, to avoid increasing unduly the weight of the shuttle and disturbing the balance thereof, it is preferably made of a light alloy or even of a hard plastic material. The insert can be in the form of a deep channel-section member, the sides of which line the sides of the shuttle slot while the tongue return spring is accommodated in the bottom of the channel, beneath the butt of the tongue. The insert is held in place by the pins serving as the pivot and the limiting stops for the shuttle tongue.

By way of example, three forms of shuttle in accordance with the invention will now be described in greater detail with reference to the accompanying drawings in which:

Figure 1 is a sectional side elevation of the end of one form of shuttle showing the arrangement for pivoting the tongue.

Figure 2 is a sectional end elevation of the shuttle shown in Figure 1, and

Figures 3 and 4 are views similar to Figure 1 of two further forms of shuttle.

The shuttle shown in Figures 1 and 2 has a wooden body 5 with inserted steel tips 6 and is formed with the usual cavity 7 for the accommodation of a pirn or other weft package (not shown). Forming an extension of one end of the cavity 7 is a narrow slot 8, the sides and bottom of which are lined by means of a light alloy member 9 of deep channel section. The shuttle tongue 10 is of the usual form, having a shank of round section carrying an arcuate spring 12 extending down one side thereof for holding in position a weft package slipped over the end of the tongue. The tongue has a butt 13 of rectangular section which fits within the side walls of the insert 9 lining the slot 8. A pin 14 passes transversely through the shuttle body 5, through the side walls of the insert 9, and through the butt 13 of the tongue 10 at a point as near as is possible to the rear end of the slot 8 while leaving the heel 15 of the butt room to swing as the tongue 10 is pivoted about the pin 14.

Near the forward edge of the slot 8 are two further pins 16, 17 passing transversely through the shuttle and serving as stops to determine the working position and the raised position respectively of the tongue 10. Round the lower pin 16 is hooked the bend of a V-shaped spring 18, the limbs 19, 20 of which are curved so as to be convex towards each other, and extend towards the rear of the shuttle. The limbs of the spring are compressed together in the space in the channel-shaped insert 9 beneath the butt 13 of the shuttle tongue, so that the lower limb 19 engages the bottom of the channel-shaped insert, while the upper limb 20 engages the underside of the butt 13. When the shuttle tongue 10 is in the working position the forward end of its butt 13 rests on the bend of the spring 18 passing round the lower pin 16, while the rearward end of the butt is pressed upwards by the upper limb 20 of the spring, so holding the tongue 10 down in the shuttle. The tongue can be lifted, for changing the weft package, until the forward end of the butt 13 engages the upper stop pin 17, at which time the upper limb 20 of the spring 18 engages the heel 15 of the butt 13 to hold the tongue 10 in the raised position.

The form of shuttle shown in Figure 3 is similar to that of Figure 1 except that there is provided an auxiliary spring 21 similar in shape to the spring 18 and hooked round an additional pin 22. The heel of the butt 13' is cut away obliquely as at 24 and is engaged by the spring 21 when the tongue 10 is in the horizontal, or working position, the pressure of such engagement assisting the spring 18 in retaining the tongue in that position. When the tongue is raised into contact with the pin 17 the spring 21 presses on the upper surface 25 of the butt 13' and assists the spring 18 in retaining the

tongue 10 in the raised position. The provision of the auxiliary spring 21 enables the spring 18 to be of material of lighter gauge and less stiffness, and so less liable to breakage in use.

Figure 4 shows a third form of shuttle in which is provided an extension 26 of the lower limb 19' of the spring 18'. The extension 26 rises behind the heel 15 of the butt 13 and presses upon it when the tongue is in the working position. The upper pin 27 which determines the raised position of the tongue 10 is disposed a little further back than the corresponding pin 17 in Figures 1 and 3, so allowing the tongue 10 to reach a more nearly vertical position better suited to the form of the spring extension 26. This modification has the advantage of that of Figure 3 and also avoids the complication of providing a second spring 21 and an additional pin 22.

Having described our invention, what we desire to secure by Letters Patent is:

1. A loom shuttle comprising a pivoted tongue for the reception of a weft package, a spring adapted to exert a pressure on the lower face of the butt of said tongue for maintaining said tongue in a working position and on the heel of said butt for maintaining said tongue in a raised position, every part of said spring whose resilience contributes to said pressure being disposed substantially wholly beneath said butt when said tongue is in the working position, said spring having a portion adapted to exert an additional pressure on the heel of said butt when said tongue is in the working position and on the upper surface of said butt when said tongue is in the raised position.

2. A shuttle according to claim 1, in which the spring is in the form of a flat spring bent through approximately 180° and hooked round a transverse pin in the shuttle, the two limbs of said spring extending rearwardly in the shuttle beneath the butt of the shuttle tongue.

3. A shuttle according to claim 1, wherein said portion of said spring exerting the additional pressure on the heel of said butt when said tongue is in the working position and on the upper surface of said butt when said tongue is in the raised position is constituted by an extension of the spring.
